Primary Examiner—Bernard Ansher*Assistant Examiner*—Prabhakar Deshmukh*Attorney, Agent, or Firm*—Jenner & Block[57] **CLAIM**

The ornamental design for a play clock tower, as shown and described.

DESCRIPTION

FIG. 1 is a perspective view of a play clock tower showing my new design;

FIG. 2 is an enlarged scale top plan view thereof;

FIG. 3 is an enlarged scale right side elevation view thereof; the left side elevation view being a mirror image except for the orientation of circular and square decorations and flag; and,

FIG. 4 is an enlarged scale front elevation view thereof. The bottom is plain and unornamented. The rear elevation portion not disclosed is unornamented.

FIG. 1

FIG. 2

FIG. 3

FIG. 4
